UNITED STATES PATENT OFFICE.

GILBERT E. JONES, OF NEW YORK, N. Y.

QUOIN.

SPECIFICATION forming part of Letters Patent No. 377,618, dated February 7, 1888.

Application filed October 28, 1886. Serial No. 217,459. (No model.)

To all whom it may concern:

Be it known that I, GILBERT E. JONES, a citizen of the United States, residing at New York, in the county and State of New York, 5 have invented new and useful Improvements in Quoins, of which the following is a specification.

This invention relates to improvements in quoins; and it consists in the features pointed out in the following specification and claims, and illustrated in the accompanying drawings, in which—

Figure 1 is a plan view of the quoin, showing the same applied to lock up matter. Fig. 2 is 15 a section in the plane $x x$, Fig. 1. Fig. 3 is a detail plan view of a quoin, the cam being removed. Fig. 4 is a detail plan view of a quoin and cam. Fig. 5 is a side elevation of Fig. 4. Fig. 6 is a section in the plane $y y$, Fig. 4. Fig. 20 7 is a section in the plane $z z$, Fig. 8. Fig. 8 is a plan view of a quoin and cam, the quoin being adapted to act as a side-lock and an end-lock. Figs. 9 and 10 show cams with engaging faces or corrugations. Fig. 11 shows a 25 quoin fixed to a side-stick.

The scale of Figs. 3 to 8, both inclusive, is larger than the scale of Figs. 1, 2, 9, 10, and 11.

Similar letters indicate corresponding parts.

In the example shown in the drawings the 30 letter A indicates the sides of a galley.

B indicates the type or matter.

C indicates the side-stick.

G is the quoin, which may be provided either 35 with a side-lock, D, or with an end-lock, E. The side-lock D presses against the side-stick C to lock up the matter. The end-lock E is adapted to lock against the end of the matter.

As seen in Figs. 1, 2, and 8, the quoin may be provided with both a side-lock, D, and an 40 end-lock, E. The end-lock E is ridged or arched, so that it can pass over the side-stick C.

The quoin G is provided with a pivot, I, on which operates a cam, F. A handle or lugs, H H, allow of a ready operation of the cam. 45 By moving or turning the cam in the proper direction the cam will press against a side A of the galley and cause the quoin to lock up the matter.

The quoin is provided with a stop, L, adapted 50 to engage a stop, K, on the cam F, as seen in Figs. 4 and 8. When the stops K L are in en-

gagement, the cam is in position to allow the quoin to be inserted into or withdrawn from the galley. The stops K L thus offer ready means for rapid operation with the quoin, as 55 by turning or moving the cam until its motion is arrested by the stops K L such cam is brought into position to allow an insertion or withdrawal of the quoin.

By fixing the lugs or handle H to the cam 60 said lugs or handle will not become detached and the quoin will always be ready for use. It should be noticed that by having the cam provided with a handle or lugs, H, as shown in the drawings, said quoin is peculiarly adapted 65 to serve as a galley-lock, as said handle or lugs allow sufficient strain to be brought on the cam to lock up the matter, but not so great a strain as to split, break, or injure a galley. In the case of those quoins where a key or 70 wrench is used the strain exerted is sometimes so great that it may split a galley; but such accident is not likely to happen when the handle H is, as shown in the drawings, affixed to the cam. The cam may also be provided 75 with flat or engaging faces or with corrugations M, as seen in Figs. 9 and 10, so that the cam will bite or securely sit against the surface with which it comes into contact, thus preventing accidental motion of the cam. The 80 quoin may also be permanently secured to the side-stick, if desired, as seen in Fig. 11, so that the side-stick and quoin will not become separated.

If desired, corrugations may also be made 85 at the side A of the galley to bite into the cam F, as seen in Fig. 9; or the cam and galley may both be corrugated, so that the galley and cam work into or engage one another, in the manner of a rack and pinion. 90

Heretofore it has been proposed to employ a rotating cam-shaped quoin turned by a key to lock up matter in a chase, and such, therefore, I disclaim. It has also been proposed to employ a combined side and end lock clamped 95 in place by a wedge, and such I also disclaim. What I claim as new, and desire to secure by Letters Patent, is—

1. The quoin G, having the side-lock D and the stop L, in combination with the cam F, 100 having faces to bear, respectively, against the side of the galley and the side-lock of the

quoins, said cam being pivoted in the upper side of the quoins and provided at its edge with the stop K, so that when turned and the stop of said cam is brought into engagement with the stop of said quoins, the latter, with its side-lock and the cam, can be introduced into or removed from the galley, substantially as described.

2. The quoins G, having the side-lock D and stop L, in combination with a galley, A, having the side-stick C, and the cam F, having faces to bear, respectively, against the side-lock of the quoins and the side of the galley, said cam being pivoted on the quoins and having a fixed and rigidly-attached lug, H, and an edge-stop, K, so that when turned and the stop of said cam is brought into engagement with the stop on the quoins, the latter, with its side-lock and the cam, can be introduced into or removed from the galley, substantially as described.

3. The quoins G, having the attached side-lock D, and provided with the stop L and vertical pivot I, in combination with the cam F, journaled in the pivot on the upper side of the

quoins and provided with the stop K, so that when rotated on said pivot to bring its stop into engagement with the stop on the quoins, the latter, with its side-lock and the cam, can be introduced into or removed from the galley, substantially as described.

4. The quoins G, having the attached side-lock D, extending laterally from each of its sides and provided with the projecting stop L and vertical pivot I, in combination with the cam F, mounted on said pivot and having faces to bear, respectively, against the galley and the side-lock on the quoins, said cam having the stop K, so that when rotated to bring its said stop into engagement with the stop on the quoins, the quoins, with its side-lock and the cam, can be removed from the galley, substantially as described.

In testimony whereof I have hereunto set my hand and seal in the presence of two subscribing witnesses.
